DESIGN FOR A GAME BOARD

Frank Gilbert Farrell, Wayne, Pa.

Application November 6, 1939, Serial No. 88,086

Term of patent 7 years

To all whom it may concern:

Be it known that I, Frank Gilbert Farrell, a citizen of the United States and resident of Wayne, Pennsylvania, have invented a new, original, and ornamental Design for a Game Board, of which the following is a specification, reference being had to the accompanying drawing, forming part thereof, in which the figure is a plan view of my new design for a game board. The article is of no appreciable or substantial thickness.

I claim:

The ornamental design for a game board, substantially as shown and described.

FRANK GILBERT FARRELL.
